[57] CLAIM

The ornamental design for a table tray attachment, as shown and described.

DESCRIPTION

FIG. 1 shows an embodiment of an ornamental table tray of my invention, slidably attached between the playing surface and frame of a conventional bridge table. A fragment of the latter is shown in phantom for illustrative purposes only.

FIG. 2 shows, in enlarged detail one embodiment of the table tray of my invention removed from attachment to the table, in perspective, as viewed from above.

FIG. 3 shows the embodiment of the table tray of FIG. 2, in perspective, turned upside down.

FIG. 4 shows, in enlarged detail an alternative embodiment of the tray of my invention, removed from attachment to the table, in perspective, as viewed from above.

FIG. 5 shows the embodiment of the table tray of FIG. 4, in perspective, turned upside down.

FIG. 6 is an enlarged fragmentary showing of one corner of the table (in phantom) looking from below, with the table tray of FIGS. 2 and 3 in storage position.

This design application was filed at even date with my utility patent application Ser. No. 724,598.
